Patented Aug. 9, 1921.

FIG. 1

FIG. 2

UNITED STATES PATENT OFFICE.

STEFAN NIKIEL, OF NEW YORK, N. Y.

FIRE-ALARM APPARATUS.

1,386,649.

Specification of Letters Patent.

Patented Aug. 9, 1921.

Application filed September 18, 1919. Serial No. 324,515.

To all whom it may concern:

Be it known that I, STEFAN NIKIEL, a citizen of Poland, residing at New York, county of New York, and State of New York, have invented certain new and useful Improvements in Fire-Alarm Apparatus, of which the following is a specification.

This invention relates to a fire alarm signal, designed to be installed at any point in 10 a building or other place where there is danger from overheating or a possible fire.

The object of this invention is to provide a means of signaling from one point to another through the medium of a wall circuit box, having direct wire connections with 15 a more or less distant signal bell, electrically connected with a low voltage battery of ordinary design.

These objects are attained by the novel 20 construction and combination of parts hereinafter described and shown in the accompanying drawings, forming a material part of this disclosure, and in which—

Figure 1 is a front plan view of a perforated metal switch box cover.

Fig. 2 is a transverse sectional view of the same, taken on line 2—2 of Fig. 1, showing the cover assembled with the box, with the interior mechanism in place.

Fig. 3 is a plan view of the switch box interior with the cover removed, and,

Fig. 4 is a side elevational view showing the signal box and connections to the battery and signal bell.

Referring to the drawings in detail, the numeral 5 designates an annular box cover pierced to present oppositely extending openings 6, its flanged portions 7 being slotted on its peripheral surface to provide 35 spring tension. A disk 9 of low fusing metal is pierced at the center by an elongated slot 10, its edge being clamped by the flange 7.

A contact arm 12, having a finger 12' engageable in the slot 10, is movably pivoted within a slotted stud 13, and insulated from the annular box body 14 by the insulation washer 15, and held by the binding nut 16 threaded on the stem of the stud 13. A 40 contact button 17, loosely attached to the arm 12, is contactable with the fixed contact button 18, insulated in a proper manner

from box body 14, by insulating washers 19, held rigidly by means of a binding nut 20, threaded on the stem of the contact button 18.

A light coiled tension spring 22, is attached at one end to an upturned pierced projection 24, the spring being secured at its opposite end to a projection 25 provided for this purpose on the arm 12.

The metal box or casing body 14, has formed in its periphery an annular recess 26, for the reception of the cover beading 27, and is attachable to the wall by means 65 of screws entered through holes 23 formed in the bottom of the box 14.

A battery 28 and an electric bell 29 suitably connected by the insulated wires 30, 31 and 32, is connected, by means of binding 70 nuts 33 and 34, to the threaded stem of the post 13 and contact button 18.

In operation, the metal box or casing 14, containing the central insulated contact button 18 and the contact arm 12 is secured in 75 position. Between the casing 14 and cover 5 is interposed the fusible disk 9, having the slot 10 into which the free end of the contact arm 12 is inserted and retained, thereby producing a definite separation of contacts 80 17 and 18.

Attached under the binding nuts 33 and 34 are insulated wires 31 and 32, making connection with one pole of the battery and one binding post of the signal bell, while 85 another insulated wire 30, completes the connection between the battery and the bell.

Should the temperature surrounding the signal box exceed the fusing point of the disk 9, the contact arm 12, carrying contact 90 17, is drawn into contact with the button 18, by the spring 22, thereby closing the electrical circuit and ringing the signal bell 29.

From the foregoing it will be obvious that 95 one or more of the alarm signal boxes may be arranged in the same circuit, at different points in the building, and should the temperature rise above the fusing point of the disk or diaphragm, an alarm will be given 100 by the bell wherever it may be located, thus affording an efficient and practical safety device in case of fire.

Having thus described my invention what

I claim as new and desire to secure by Letters Patent, is—

In a circuit closer of the character described, in combination, a metal casing, a central contact button in said casing insulated therefrom, a contact arm, a contact on said arm, a disk of low fusing metal in said casing having a central slot and adapted

to be normally engaged by the end of said arm, and a spring adapted to draw both contacts into engagement upon the fusing of said disk, disengaging said arm therefrom for closing a signal circuit. ¹⁰

In testimony whereof I have affixed my signature.

STEFAN NIKIEL.
